ASSIGNORS TO THE WATAIRWAY MANUFACTURING CORPORATION, OF NEW YORK,
N. Y., A CORPORATION OF NEW YORK

SANITARY WATER CLOSET ATTACHMENT

Application filed November 20, 1930. Serial No. 496,898.

This invention relates to plumbing appliances and more particularly refers to improvements in sanitary attachments for water closets and bidets of the type where a jet of water is used instead of paper for personal cleansing purposes.

The idea of equipping a water closet or bidet with means for directing a jet of water against the body of the user for sanitary purposes, is not in a broad sense new. Appliances of this type however, have heretofore generally been made in forms requiring a special construction of water closet bowl, or else in forms adapted to be attached to water closets having specially provided attaching means.

In either case, the necessity of making special provisions for the sanitary feature thus added is effective in considerably curtailing the practical field of its application, limiting its use as it does to new or specially equipped bathrooms.

In two other patent applications, entitled Method of and apparatus for sanitary cleansing, Serial No. 483,284 and Cleansing nozzle for water closet, Serial No. 485,440 filed by us, arrangements have been described, comprising sanitary attachments in unitary form, said attachments comprising a stand upon which all the operating parts are mounted, said stand having a base adapted to be placed upon the floor alongside the toilet bowl.

We have found by experience that in certain instances, it is desirable to avoid the use of a floor stand. In some cases, the required floor space is not available and in all cases the installation entails the necessity of drilling the floor and embedding therein some suitable attaching means such as expansion bolts or wood blocks, requiring the use of some cement or similar plastic material. These operations usually must be performed by men experienced in this class of work, and this represents a source of considerable expense which must be added to the expense entailed by the connection of the device to the sources of fluid supply, requiring operations which are purely within the scope of a plumber's work.

Due to the conditions thus engendered by the use of devices in stand form, the installation expenses come to represent a material portion of the total cost, and are frequently such as to make it impractical to adopt this class of devices in existing water closets.

The primary object of our invention is to provide a sanitary attachment for water closets which is built complete in unit form but which does not require any stand or other means of attachment to the floor or walls, said attachment being adapted to be mounted directly upon the bowl of the water closet or bidet.

Another object is to provide a device of the character specified adapted to be mounted upon and adjusted along the rim of the water closet bowl, so as to be easily placeable in the best position required by its operation.

A further object is to provide a device of the character specified requiring a minimum amount of labor for its installation both from the standpoint of its placement in position and from the standpoint of connecting it to a source of water supply.

A still further object is to provide in a device of the character specified, a novel and improved arrangement of controlling mechanism, whereby a single moving part may be used to move a fluid delivery arm to its operative position and to control the fluid supply to said arm.

Other objects and advantages of the present invention will more fully appear as the description proceeds and will be set forth and claimed in the appended claims.

Our invention is illustrated by way of example in the accompanying drawings, in which:

Fig. 1 is a plan view of a water closet bowl equipped with our improved device;

Fig. 2 is a side elevation of said bowl;

Fig. 3 is a vertical longitudinal section of said bowl through line 3-3 of Fig. 1;

Fig. 4 is a fragmentary vertical section of said bowl through line 4-4 of Fig. 1;

Fig. 5 is a plan view of our device in an enlarged scale;

Fig. 6 is a side view in elevation thereof; 100

Fig. 7 is a fragmentary vertical section of the same through line 7-7 of Fig. 5; and

Fig. 8 is a fragmentary section of said device through line 8-8 of Fig. 5 with parts broken away, to show the construction of the plunger.

Referring to said drawings, 20 designates a toilet bowl of usual construction, comprising a base 21 and a rim 22 formed with a passage 23 through which water flows from a suitable source of supply in order to flush the bowl in the customary manner.

The bowl is provided with a seat 24 on top hinged at 25 to the rear of the bowl. The lower surface of the seat 24 is usually provided with rubber spacing heads resting upon the top of rim 22, causing a clearance 26 to remain between the top of the bowl and the lower surface of the seat.

Our device proper comprises a supporting bracket 29 upon which all the operating parts are mounted, said bracket having two hook shaped arms 30, 31, inwardly extending therefrom, said arms being adapted to embrace the rim portion of the bowl so as to secure the device in position.

To this end, arms 30, 31 are composed of a horizontal section 32 inwardly extending from the platform 33 of bracket 29, and a downward turned end section 34 embracing the inner portion of rim 22. Arms 30, 31 are preferably secured onto the bracket by means of screws such as 35 so as to make it easier to set the device in position and to remove it therefrom.

The bracket is also provided with a central clamping screw 36 which may be moved towards or away from the outer surface of bowl rim by means of adjusting nut portion 37. By means of said screw the bracket can be caused to firmly grip the rim portion of the bowl so as to provide a stable support for the operating parts of the device.

In order to increase the stability of the bracket and prevent the possibility of its tilting when downward pressure is exerted against it, said bracket preferably also is formed with a downwardly directed extension 38 equipped with an adjusting screw 39 at its lower end, said screw resting against the side surface of the bowl at a distance from the top thereof.

Said bracket furthermore, comprises an outward substantially horizontal extension 40 upon which is mounted a vertical tubular shell 41, forming the body of the device. On said extension and coaxial with shell 41 is also rotatably mounted an arm carrier 42 which is formed with a downward projection 43 acting as a pivotal support therefor. Said arm carrier is formed with a central chamber which is divided by a partition 44 into a lower or inlet chamber 45 and an upper or delivery chamber 46, the communication between said two chambers being controlled

by a valve 47 carried by a vertically movable stem 48.

When the device is inoperative, communication between chamber 45 and chamber 46 is cut off by said valve, said valve being urged upwardly by the action of a spring 49 interposed between the lower surface of said valve and the lower surface of chamber 45.

The portion of extension 40 upon which projection 43 is rotatably mounted is formed with an annular chamber 50 which may be connected to a source of water supply by a pipe 51. Projection 43 is provided with an axial passage 52 which extends horizontally at its lower end, to communicate with chamber 50 as shown at 53.

Shell 41 is formed with a horizontal segmental slot 54 through which is inserted the inner end 55 of water delivery arm 56, said end 55 being screwed onto the side of arm carrier 42 and communicating with chamber 46.

The water delivery arm which is shown in Fig. 5 in its operative position is angularly movable together with arm carrier 42 about the axis of shell 41, between two extreme positions which are defined by the angular extension of slot 54. Said arm comprises a horizontal section 57 which extends substantially on a level with horizontal sections 32 of arms 30, 31 and which moves therebetween, said arms 30, 31 being spaced from each other a distance sufficient to allow the free and unhampered angular movement of said delivery arm.

The length of horizontal section 57 of the water delivery arm is such as to cause said horizontal section to reach just beyond the inner edge of rim 22. At this point, the arm is bent downwardly and inwardly to embrace the inner portion of said rim and is then bent forwardly along a horizontal curve to form a nozzle carrying extension 58 which closely follows the curve of the inner surface of the bowl when the device is in its inoperative position and the water delivery arm occupies the position shown in dotted lines in Fig. 1 at 57', 58'.

The device is so arranged that when the water delivery arm occupies its inoperative position, the connection between chamber 45 and chamber 46 is cut off by valve 47 while after the water delivery arm has been brought to its operative position shown in full lines in Figs. 1 and 5, valve 47 is depressed so as to establish communication between said two chambers, allowing water supplied through pipe 51 to flow through chamber 50, passage 52, chamber 45 and chamber 46 and thence through the water delivery arm and the nozzle 59 carried by the outer end of extension 58.

When the water delivery arm is moved to its operative position, nozzle 59 preferably comes to occupy a position within the bowl

in which its axis remains on a vertical longitudinal plane passing through the center of the bowl, and is upwardly inclined towards the rear of the bowl, as advocated in our co-pending application No. 483,234. Water under pressure issuing from the nozzle will therefore be projected in an upwardly inclined direction towards the rear of the bowl. More particularly, the direction of the fluid jet issuing from the nozzle will be so arranged that the fluid under pressure will strike directly against the body outlet of the occupant of the seat in connection with which the cleansing operation is to be performed.

The cylindrical outer surface of arm carrier 42 forms with the inner surface of shell 41 an annular chamber 60 within which is inserted the sleeve portion 61 of operating plunger 62, the upper part of said plunger being formed with a brass knob 63. The sleeve portion of said plunger is mounted within chamber 60 so as to be axially slideable therein. Said plunger however, is restrained against rotation by a key 64 in a well known manner.

The sleeve portion 61 of said plunger is provided with a slot 65 which extends from a lower end 66 to an upper end 67, the inner end 55 of delivery arm 56 passing through said slot. The vertical extension of said slot therefore, determines the two extremes of the possible vertical displacement of the plunger. The upper portion of said slot consists of a vertical tract 68, and the lower portion of the slot consists of a portion 69 which is inclined and which connects the lower end of vertical tract 68 with the lower end 66 of the slot. The angular extension of the slot determined by the inclination of tract 69 substantially corresponds to the angular extension of slot 54, so that when the plunger is in its upper or inoperative position the lower end 66 of slot 65 registers with the left end of slot 54 and when the plunger is moved to its operative position the upper end 67 of slot 65 registers with the right end of slot 54, with respect to Fig. 8.

By virtue of this construction, it will be seen that slot 65 acts as a cam controlling the movement of the fluid delivery arm, causing it to occupy its inoperative position when the plunger is in its upward position shown in Fig. 7, and causing said arm to move to its operative position when said plunger is forced downwardly a distance corresponding to the vertical extension of inclined tract 69 of slot 65.

Plunger 62 is normally maintained in its upward or inoperative position by the action of a spring 70 interposed between the lower surface of knob 63 and the upper surface of a packing nut 71 carried by cover 72 of chamber 46, said packing nut insuring the tightness of the passage through which stem 48 extends upwardly from chamber 46.

The upper end 73 of stem 48 is spaced from the lower surface 74 of knob 63 a distance substantially corresponding to the vertical extension of inclined tract 69 of slot 65. It will therefore be seen that when plunger 62 is forced downwardly by the hand pressing against knob 63, the fluid delivery arm is first moved from its operative to its inoperative position by the cam action of inclined tract 69, of slot 65. As soon as the operative position of said arm has been reached, the lower surface 74 of knob 63 strikes against the upper end 73 of stem 48, depressing valve 47 and water can then enter chamber 46 and reach the delivery arm and nozzle 59 through the seat of said valve, said valve being depressed against the action of spring 49.

As soon as the pressure exerted against knob 63 is released, spring 70 will force the plunger upwardly to its normal or inoperative position, and inclined tract 69 of slot 65 will at the same time cause the fluid delivery arm to return to its normal inoperative position. During the first part of the upward movement of the plunger, valve 47 will also be forced upwardly to its closing position by the action of spring 49 so that when the fluid delivery arm begins to move back no more water issues from nozzle 59.

It is, of course, possible to connect pipe 51 to both a source of cold water supply and a source of warm water supply; or else, if desired, it is possible to insert in said pipe an instantaneous electric water heater as shown at 75 in Fig. 1. The type of bracket described provides a very strong supporting structure for the various operating parts which does away entirely with the necessity of providing a separate floor or wall stand. Such a structure is much less expensive than a floor or wall stand and does not require a skilled worker for setting it in place. It will also be observed that the manner of operation of the device is exceedingly simple, requiring but one movement for controlling the operation of the fluid delivery arm and the supply of water thereto.

Due to its simplicity and relatively low cost, the device can be installed in many places where the cost of a device such as described in the copending applications above mentioned would be prohibitive. Furthermore, the device occupies a very limited amount of space and therefore the same can be installed in places where a device mounted on a stand could not be used.

The constructional details of our invention may vary from those shown without departing from the inventive idea. The drawings should therefore be understood as being intended for illustrative purposes only and not in a limiting sense. Accordingly, we reserve the right to carry our invention into practice in all those ways and manners which may en-

ter, fairly, into the scope of the appended claims.

We claim:

1. In apparatus of the class described, adapted for use in connection with a closet bowl, the combination, with a fluid delivery arm movable between two extreme positions within said bowl, of a supporting bracket for said arm, hook-shaped means inwardly extending from said bracket, for resting said bracket onto, and embracing the rim of said bowl, and adjustable means, carried by said bracket, movable against the outer surface of said bowl, for securely clamping said bracket onto said rim.
2. In apparatus of the class described, adapted for use in connection with a closet bowl, the combination, with a fluid delivery arm movable between two extreme positions within said bowl, of a supporting bracket for said arm, having a downwardly extending projection, hook-shaped means inwardly extending from said bracket, for resting said bracket onto, and embracing the rim of said bowl, adjustable means, carried by said bracket, movable against the outer surface of said bowl, for securely clamping said bracket onto said rim, and adjustable means, carried by said projection, movable against the outer surface of said bowl, to prevent tilting of the supporting bracket.
3. In apparatus of the class described, adapted for use in connection with a closet bowl, the combination, with a fluid delivery arm having a discharge end extending within said bowl, of a pivotally mounted arm carrier angularly movable about a vertical axis so as to move said arm between two extreme positions, a support therefor, normally closed means for supplying cleansing fluid to said arm, controlling means therefor, and a depressible plunger member normally retaining said arm and arm carrier in their inoperative position, said plunger member, when depressed, first causing angular movement of said arm and arm carrier to their operative position, then actuating said fluid supply controlling means to admit cleansing fluid to said arm after said arm has reached its operative position.
4. In apparatus of the class described, adapted for use in connection with a closet bowl, the combination, with a fluid delivery arm having a discharge end extending within said bowl, of a pivotally mounted arm carrier angularly movable about a vertical axis so as to move said arm between two extreme positions, a support therefor, a casing surrounding said arm carrier and forming an annular chamber therewith, a segmental horizontal slot through said casing, forming a passage for said arm, and a depressible plunger member movable within said annular chamber, said plunger member having a cam-acting slot through which said arm is

inserted, said slot having an inclined lower tract and a vertical upper tract, so as to cause angular movement of said arm and arm carrier from one extreme position to the other, during the first portion of the downward movement of said plunger, when said plunger is depressed, and so as to retain said arm and arm carrier in said other extreme position, while said plunger continues its downward movement.

5. In apparatus of the class described, adapted for use in connection with a closet bowl, the combination, with a fluid delivery arm having a discharge end extending within said bowl, of a pivotally mounted arm carrier angularly movable about a vertical axis so as to move said arm between two extreme positions, a support therefor, a casing surrounding said arm carrier and forming an annular chamber therewith, a segmental horizontal slot through said casing, forming a passage for said arm, and a depressible plunger member movable within said annular chamber, said plunger member having a cam-acting slot through which said arm is inserted, said slot having an inclined lower tract and a vertical upper tract, so as to cause angular movement of said arm and arm carrier from one extreme position to the other, during the first portion of the downward movement of said plunger, when said plunger is depressed, and so as to retain said arm and arm carrier in said other extreme position, means for admitting cleansing fluid to said carrier and arm, a normally closed valve controlling said fluid admitting means, while said plunger continues its downward movement, said plunger actuating said valve to admit cleansing fluid to said carrier and arm, during the second portion of its downward movement, after said carrier, and arm have reached said other extreme position.

6. In apparatus of the class described, adapted for use in connection with a closet bowl, the combination, with a fluid delivery arm having a discharge end extending within said bowl, of a pivotally mounted arm carrier angularly movable about a vertical axis so as to move said arm between two extreme positions, a support therefor, normally closed means for supplying cleansing fluid to said arm, controlling means therefor a depressible plunger member normally retaining said arm and arm carrier in their inoperative position, said plunger member, when depressed, first causing angular movement of said arm and arm carrier to their operative position, then actuating said fluid supply controlling means to admit cleansing fluid to said arm after said arm has reached its operative position, and means for detachably securing said support onto the rim of said bowl.

7. In apparatus of the class described, adapted for use in connection with a closet bowl, the combination, with a fluid delivery

- arm having a discharge end extending within said bowl, of a pivotally mounted arm carrier angularly movable about a vertical axis so as to move said arm between two extreme positions, a support therefor, a casing surrounding said arm carrier and forming an annular chamber therewith, a segmental horizontal slot through said casing, forming a passage for said arm, a depressible plunger member movable within said annular chamber, said plunger member having a cam-acting slot through which said arm is inserted, said slot having an inclined lower tract and a vertical upper tract, so as to cause angular movement of said arm and arm carrier from one extreme position to the other, during the first portion of the downward movement of said plunger, when said plunger is depressed, and so as to retain said plunger member in its upward position.
8. In apparatus of the class described, adapted for use in connection with a closet bowl, the combination, with a fluid delivery arm having a discharge end extending within said bowl, of a pivotally mounted arm carrier angularly movable about a vertical axis so as to move said arm between two extreme positions, a support therefor, a casing surrounding said arm carrier and forming an annular chamber therewith, a segmental horizontal slot through said casing, forming a passage for said arm, means for admitting cleansing fluid to said carrier and arm, a normally closed valve controlling said fluid admitting means, a depressible plunger member movable within said annular chamber, said plunger member having a cam-acting slot through which said arm is inserted, said slot having an inclined lower tract and a vertical upper tract, so as to cause angular movement of said arm and arm carrier from one extreme position to the other, during the first portion of the downward movement of said plunger, when said plunger is depressed, and so as to retain said arm and arm carrier in said other extreme position, while said plunger continues its downward movement, said plunger member actuating said valve to admit cleansing fluid to said carrier and arm, during the second portion of its downward movement, after said carrier and arm have reached said other extreme position, and a spring normally retaining said plunger member in its upward position.
9. In apparatus of the class described for use in connection with a closet bowl, a nozzle movable to and from an operative position within said bowl, normally closed means for supplying fluid to said nozzle, controlling means therefor, and means movable in a given direction for moving said nozzle from an inoperative to its operative position, said nozzle moving means being adapted to continue moving in the same direction and actuating said fluid supply controlling means, only after said nozzle has reached its operative position.
10. In apparatus of the class described for use in connection with a closet bowl, a nozzle movable from an inoperative position to an operative position within said bowl, normally closed means for supplying fluid to said nozzle, controlling means therefor, and a single member for actuating said nozzle and said fluid supply controlling means, said member by a single movement first moving said nozzle to its operative position then actuating said fluid supply controlling means to supply fluid to said nozzle.
11. In apparatus of the class described for use in connection with a closet bowl, a nozzle movable from an inoperative position to an operative position within said bowl, normally closed means for supplying fluid to said nozzle, controlling means therefor, a single member for actuating said nozzle and said fluid supply controlling means, said member by a single movement in the same direction, first moving said nozzle to its operative position then actuating said fluid supply controlling means to supply fluid to said nozzle, and means for retaining said nozzle in its operative position while said actuating member continues its movement to actuate said fluid supply controlling means.
